(57) CLAIM

The ornamental design for electro-less lamp assembly, as shown and described.

DESCRIPTION

FIG. 1 is a perspective view of an electro-less lamp assembly showing our new design;

FIG. 2 is a side view thereof;

FIG. 3 is a top view thereof; and,

FIG. 4 is a bottom view thereof.

The broken line shown of environment and all views are for illustrative purposes only and forms no part of the claimed design.
